ABSTRACT OF THE DISCLOSURE

Explosive compositions characterized by very high detonation velocities, excellent cratering performance, high blast effect, and useful impact sensitivity characteristics, and comprising hydrazinium nitrate or mixtures of hydrazinium nitrate and ammonium nitrate (with optional minor proportions of alkali metal nitrates and/or alkali metal perchlorates and/or calcium nitrate and/or calcium perchlorate), together with hydrazine or mixtures of hydrazine and ammonia, and with finely divided aluminum as a reducer reactant. The explosive composition can further comprise optional physical property modifying additives, such as desensitizing agents, thickening and gelling agents, freezing point depressants, and waterproofing agents. Also presented are methods of preparation of the compositions, including the preparation of pre-mixed non-explosive components, a first such component being hydrazine or like liquid containing a non-explosive amount of the oxidizer salt(s), and a second such component being essentially the additional oxidizer salt(s). Relative percentages by weight of the significant ingredients are as follows: Aluminum particles, from about 2% to about 45%; NH₃ and NH₄⁺, from 0% to about 18%; N₂H₄ and N₂H₅⁺, from about 6% to about 75%; NO₃[—] or equivalent anion, from about 14% to about 70%. Optionally, minor proportions of the nitrate or equivalent anion can be present in the form of certain metallic and/or perchlorate salts. Various physical property modifiers can also be included in the composition.

CROSS REFERENCES TO RELATED APPLICATIONS

This application is a continuation-in-part of Bridgforth and Sutherland U.S. application Ser. No. 340,127, entitled Stable, High Energy Compositions, and filed Jan. 27, 1964.

This application is also a continuation-in-part of Maes U.S. application Ser. No. 631,123, entitled Hydrazine Containing Explosive Compositions, filed Apr. 17, 1967, and issued as U.S. Pat. No. 3,419,443 on Dec. 31, 1968.

BACKGROUND OF THE INVENTION

Field of the invention

The invention pertains to explosive compositions and methods, characterized by a hydrazinium nitrate/hydrazine/aluminum explosive system, together with labile equilibrium amounts of ammonium nitrate and ammonia in some instances, and together with various physical property modifiers to provide appropriate stability, density, viscosity, and freezing point characteristics in the composition.

Description of the prior art

Explosive and propellant compositions are generally known which involve mixtures of hydrazine and hydrazinium nitrate (also known as hydrazine nitrate or hydrazine mononitrate) such as are disclosed in Audrieth U.S. Pat.

2

No. 2,704,706 and Audrieth et al. U.S. Pat. No. 2,943,927. U.S. Pat. No. 2,704,706 discloses ammonium nitrate sensitized with hydrazinium nitrate for use in conjunction with a known explosive such as TNT, the nitrates being in solid form and without any free hydrazine present. In U.S. Pat. 2,943,927 a hydrazine-hydrazinium nitrate system is noted as having a characteristically low freezing point and having utility for use as a fuel in conjunction with conventional oxidizers such as hydrogen peroxide, fuming nitric acid and liquid oxygen, the hydrazine-hydrazinium nitrate in this instance including at least about 18% hydrazine by weight, and optimally about 50% or more by weight of hydrazine, to provide a freezing point for the fuel of some —50° C. In the Audrieth et al. fuel, as is above noted, the proportionation of the hydrazine-hydrazinium nitrate mix is determined solely by consideration of freezing point depression, and not by any consideration of stoichiometric balance or maximal efficiency as an explosive composition, and more particularly does not involve any consideration of stoichiometric balance or maximal efficiency in the situation where the hydrazine-hydrazinium nitrate mix is employed in conjunction with an uncombined metal reducer constituent such as aluminum, as in the case of the present invention.

Also previously known are explosive compositions containing ammonium nitrate, together with a hydrogen-containing solvent therefor, such as liquid ammonia or ammoniacal ammonium nitrate solutions, and with a metallic fuel constituent such as aluminum or magnesium particles, which type of explosive composition is disclosed in Hradel U.S. Pat. No. 3,124,495. In these compositions the ammonia or like solvent for the ammonium nitrate is present in a proportion of from about 2% to about 35% by weight, as compared with the ammonium nitrate present in the proportion of about 10% to about 83% by weight, and the metal constituent is present in the amount of from about 15% to about 60% by weight. In the Hradel explosive composition the particle size of the metal constituent is stated to be essentially greater than 20 U.S. standard sieve, in order that the composition be satisfactorily insensitive from the point of view of avoidance of premature detonation during handling. While Hradel presents a general statement as to the hydrogen-containing solvent for the ammonium nitrate being either liquid ammonia, water, ammonium hydroxide, or hydrazine (with all examples presented involving ammonia in aqueous solution as the solvent), Hradel makes no distinction with regard to various solvents, nor any comprehension as to any particularly advantageous physical properties or detonation characteristics of particular combinations of hydrazine or hydrazine containing solvent with a nitrate or the like oxidizer dissolved therein and in the presence of aluminum particles, such as characterizes the present invention. The Hradel contribution to the art is in effect only an ammonia-ammonium nitrate/aluminum or magnesium type explosive system. This is apparent from the fact that hydrazine and magnesium can be exothermically unstable and yield a spontaneously combustible composition.

SUMMARY OF THE INVENTION

In comparison with the Hradel explosive system, the hydrazinium nitrate/hydrazine/aluminum explosive system of the invention has free hydrazine present which, even if present in excess, is peculiarly non-deleterious to the explosive reaction, since it of itself decomposes to gaseous products with energy release, whereas the ammonia or ammonia and water liquid constituent of Hradel requires energy for decomposition and thus detracts from the explosive energy release. To be considered as well is the circumstance that hydrazine is much more than a simple solvent in the explosive system of the present in-

vention, since it also forms unique intermediate reaction products (theorized to include AlN, for example) which result in a higher and more rapid energy release. Hydrazine also serves as a uniquely effective working fluid in the present explosive system, resulting in more energy contribution to the mixture as it reacts to gaseous end products, adding substantially more gas per initial unit weight of the composition. Perhaps of most significant importance in comparing the ammonia/ammonium nitrate/aluminum or magnesium explosive system of Hradel with the hydrazine/hydrazinium nitrate/aluminum explosive system of the present invention is the consideration that the Hradel "liquor" (the normally liquid portion of the composition, i.e. ammonium nitrate dissolved in ammoniacal aqueous solution) is not detonable in the absence of the metal constituent, whereas the "liquor" of the present invention (e.g. ammonium nitrate dissolved in hydrazine to form an ionic equilibrium of hydrazinium and ammonium cations and nitrate anions along with substantial amounts of free hydrazine and also free ammonia being present) is of itself explosive without the metal (aluminum) constituent. The explosive system of the present invention is consequently theorized to provide what may be termed a two-stage explosive system, with the initial explosive shock wave being caused primarily by the reaction of the oxidizer and the hydrazine, with the reaction of the metal constituent apparently occurring in two stages to provide an after shock. As a result of such two stage reaction of the aluminum constituent, optimized formulations characteristic of the present invention demonstrably provide about twice the air shock of TNT, whereas the air shock performance of the Hradel explosive system is about the same as that of TNT.

To further compare the nature of the respective explosive reactions of the Hradel type explosive system and that of the present invention, it is theorized that a typical Hradel type explosive reaction proceeds as follows:

Also for comparison purposes, a typical ammonium nitrate/aluminum/water explosive system is theorized as reacting as follows:

By comparison, the reactions characterized the explosive system of the present invention are theorized to be as follows:

The aluminum nitride intermediate product unique to the explosive composition of the present invention is theorized as providing the two stage explosive reaction and increased burst effect characterizing the invention, as above discussed.

To further summarize the nature of the present invention, it has been determined that explosive compositions according to the invention should include the following constituents, present in the following approximate relative percentages by weight:

Constituent	Broad range	Preferred range	Optimized formula
Aluminum	2-45	2-35	33
NH_4^+ and NH_3^+	0-18	0-10	10
N_2H_4^+ and N_2H_5^+	6-75	15-30	19
NO_3^- or equivalent	14-70	25-55	38

With regard to the above constituent formulations, the nitrate ion or equivalent can be present in one or more compounds selected from the group consisting of nitrate(s) and mixtures thereof with minor amounts of perchlorate(s). Optionally, the oxidizer salt can also include minor amounts of one or more oxidizer salts having certain metallic cations in lieu of a stable hydronitrogen

type cation, i.e. the oxidizer salt(s) can include a minor proportion of an oxidizer salt selected from the group consisting of alkali metal nitrates, calcium nitrate, aluminum nitrate, hydrazinium perchlorate, alkali metal perchlorates, calcium perchlorate, and mixtures thereof. However, in the usual application of the explosive composition, the presence of a minor amount of metallic cation offers no advantage and to an extent detracts from the explosive efficiency of the composition in that the metallic cation forms a solid reaction product rather than gaseous reaction product. In some instances, however, a minor amount of a metallic cation in the oxidizer salts is beneficial from the point of view of reducing foaming during composition preparation, or from the point of view of improved storage characteristics or other desired physical properties.

The explosive compositions of the present invention in general can be formulated either by mixing ammonium nitrate and hydrazine with subsequent aluminum particle addition, or by mixing hydrazinium nitrate with hydrazine with subsequent aluminum particle addition. In the first instance, the nitrate is present in the final mix in the form of hydrazinium nitrate and ammonium nitrate in labile equilibrium with hydrazine and ammonia. In the second instance the nitrate ion is present essentially in the form of hydrazinium nitrate without substantial ammonium nitrate being present. As a variation of the first manner of composition formulation, and to arrive at a composition wherein the nitrate is present essentially entirely as hydrazine nitrate with essentially no ammonium present, the mixing of ammonium nitrate and hydrazine can proceed at elevated temperature and/or under vacuum to remove evolved gaseous ammonia. Considering the type of explosive composition resulting from the first above-discussed mode of preparation, i.e. the type of explosive composition which incorporates a mixture of hydrazinium nitrate and ammonium nitrate in labile equilibrium with hydrazine and ammonia, from the point of view of the approximate relative percentages by weight of the starting materials, the explosive compositions according to the invention include the following constituents in the following approximate percentages:

Constituent	Broad range	Preferred range	Optimized formula
Aluminum	2-45	20-35	33
NH_4NO_3	18-92	32-70	48
N_2H_4	6-75	15-30	19

In the instances resulting in an explosive composition wherein the nitrate ion is present essentially entirely in the form of hydrazinium nitrate, the proportioning of the hydrazinium nitrate and the hydrazine in the above tabulation becomes the following:

Constituent	Broad range	Preferred range	Optimized formula
$\text{N}_2\text{H}_5\text{NO}_3$	21-95	38-83	57
N_2H_4	3-77	7-30	10

Also to be considered with respect to relative proportioning is the commonly used thickening and/or gelling agent incorporated in the explosive mix. With respect to such agent, and as a percentage of the total explosive mixture by weight, the broad range of the thickening and/or gelling agent is about 0-20%, the preferred range is about 1-5%, and the optimized proportion is about 3%.

Thickening and/or gelling agents are usually added to the explosive compositions of the invention to maintain the finely divided aluminum in substantially uniform distribution in the explosive mix, which is otherwise in many instances a liquid slurry by reason of the hydrazine containing solvent and dissolved oxidizer constituents being in liquid or liquid slurry form. Thickening or gelling of the composition can be accomplished by a variety of additional agents, generally known per se for the purpose, added in desired amounts up to about 20% by weight. Typical thickening and gelling agents are Cab-O-Sil (a finely divided SiO_2 thickening agent, suitably usable in

proportions up to about 10% by weight) and Quartec 503 (a cross linking gelling agent, suitably used in proportions up to about 5% by weight). Another useful gelling agent is Carbopol, for example. Gelling agents are commonly furnished in the form of a powder, and such powder can be added to the liquid mix or a liquid constituent prior to addition of one or more of the other explosive constituents. Thus, for example, the gelling agent suitably can be added to the hydrazine along with and as a pre-mixed addition to the solid ammonium nitrate. The addition of Quartec 503 to the explosive is also advantageous in terms of waterproofing the explosive for many usages thereof, such as ground placed applications where in-place pickup of environmental water could otherwise unduly desensitize the explosive. Carbon black is also effective thickening agent, and typifies agents of this type which function without also being a gelling agent.

In many applications of the explosive composition it is also desirable to add a desensitizing agent to inhibit sensitivity of the composition, either during the manufacturing process or during use. Water is an effective desensitizer and, while it does have a pronounced effect on the energy characteristics, water can be a desirable desensitizer in amounts up to about 10% by weight in certain mixes. Other effective desensitizing agents are glycerin, glycol, wax, and various hydrocarbon oils, such as stove oil, for example. In the instance of stove oil, the proportion of oil desensitizer can be up to about 20% of the total explosive mix, by weight. In the case of a solid but liquidifiable desensitizer such as wax, the desensitizer is suitably heated and mixed in the composition at elevated temperature, resolidifying and contributing to the thickening of the composition upon cooling thereof. In general, any non-volatile material which exhibits storage stability in admixture with the hydrazine/hydrazine salt components of the explosive can act as a desensitizer.

Some explosive compositions contemplated by the present invention have a freezing point near normal temperature and thus make it desirable to have included therein a freezing point depressing agent. An example of a compatible freezing point depressant for the purpose is hydrazinium thiocyanate (N_2H_5SCN).

The above and other physical property modifiers are further discussed in relation to hydrazinium and hydrazinium nitrate containing explosive compositions in the aforesaid U.S. application 340,127, and U.S. Pat. 3,419,443. To the extent here pertinent, disclosures of said application and said patent having to do with similar hydrazine and hydrazinium nitrate containing explosive compositions and having to do with various properties and characteristics thereof, as well as the effect and equivalency of various active constituents and various physical property modifiers therein, are hereby incorporated in this disclosure by reference.

DESCRIPTION OF PREFERRED EMBODIMENTS

A comparison example of cast TNT and various explosive compositions typical of the present invention were formulated with ingredient proportions as set forth in the following Table 1:

TABLE 1

Example:	Formulation (parts by weight)				Cratering Performance (1 lb. shots buried 20" in sandy loam)	
	N_2H_4	NH_4NO_3	Al	Other	Depth	Diam.
X	(1)				33	53
1	40	100	68	4 Cab-O-Sil	40	80
2	40	100	47	do	36	75
3	40	100	36	do	37	73
4	70	80	54	do	36	71
5	40	100	68	4 Cab-O-Sil, 10 water	40	84

¹ Cast TNT.

In each of the instances of Examples 1-5, a first non-explosive liquid component was first prepared by dissolving about 5 parts of the ammonium nitrate in the

hydrazine at room temperature. When this solution had normalized, the remainder of the ammonium nitrate and the thickening agent were added with stirring to cause substantially complete dissolution of the nitrate in the hydrazine. The aluminum powder (Reynolds atomized aluminum A-1511, with particle sizes predominantly in the range of 30-40 microns) was then progressively added while the mixture was stirred with a Lightening mixer (1750 r.p.m.) and agitation was continued until the viscosity of the mixture was sufficient to prevent the aluminum particles from settling out. Three one pound charges were then prepared in each instance, the container used for the Examples 1-5 being a conventional Boston Round one pint polyethylene bottle. All shots were boosted with 50 gram tetryl pellets and initiated with Dupont SSS seismograph blasting caps EB, with the detonator-booster assemblies packaged in a polyethylene bag to prevent reaction with the explosive, the polyethylene bottle being cut from the side above its explosive contents for insertion of detonator-booster assembly bag and egress of the detonator leads. All charges were then buried to a depth of 20 inches in similar sandy loam earth. All charges were placed container bottom down and tamped in the blast holes, the depth of placement measurement being to the bottom of the explosive charge.

Cratering performance was measured in terms of blast crater depth in inches to solid ground at the center of the crater, and in terms of average diameter of the crater, the average diameter being determined by the average of four diameters across the crater. Cratering performance of the various Examples 1-5 and the comparison Example X were as shown in the above tabulation. The improvement in cratering performance of all of the examples, in comparison with the cast TNT charge (Example X) is apparent. Also apparent is the circumstance that the proportion of aluminum is not particularly critical (comparing about 20% aluminum in Example 3 with about 32.7% aluminum in Example 1), and that presence of a substantial amount of water (about 5% in Example 5) does not materially change the cratering performance (comparing Examples 1 and 5).

Example 6

To further characterize the properties of typical explosive compositions, the explosive of Example 1, prepared as above indicated, was determined to have a density of 1.61 at 69° F. and a sensitivity of 70 kg./cm. For comparison purposes, an Example 6 composition was formulated, involving the same ingredient proportions as in Example 1 (except for 3 parts Cab-O-Sil), the hydrazine in this instance being preheated to 150 F. then added to the ammonium nitrate slowly with agitation, followed by heating of the mix to 120° F. to completely dissolve all of the nitrate in the solution and to evolve gaseous ammonia. This procedure resulted in a detonable composition having a comparable sensitivity and a density of 1.752 at 68° F.

Example 7

To show the effect of a desensitizer on cratering performance, the explosive composition of Example 1 (with

3 parts Cab-O-Sil) was compared with an Example 7 explosive composition containing the ingredients of Example 1 plus 21% glycerin by weight. Performance tests

showed this mixture was markedly desensitized but still detonatable. Specifically, the Example 1 composition yielded cratering 36½ inches deep and 115 inches in diameter, while the desensitized composition yielded cratering 26 inches deep and 68 inches in diameter. Related tests involving variation of glycerin proportion from 16% to 22% indicated none of the compositions were cap sensitive but were rifle impact sensitive in rubber lined cast iron pipe, with low order detonations at 20% glycerin and below.

Examples 8 and 9

To further examine cratering performance of a desensitized explosive composition, an Example 8 composition was prepared incorporating with the formulation of Example 1 5% by weight of stove oil and an Example 9 composition was also prepared which included 10% stove oil with the formulation of Example 1. Example 8 proved to be both rifle bullet (.30-06) impact sensitive and cap sensitive, whereas Example 9 proved both rifle impact insensitive and cap insensitive. Boosted with 50 grams tetryl, both Examples 8 and 9 proved detonable, and Example 9 produced a crater 42½ inches deep and 94 inches in diameter, as compared with an Example 1 formulation crater 43½ inches depth and 114 inches diameter.

Example 10

The formulation of Example 1 compounded with 0.1% by weight Quartec 503 and 4 parts Cab-O-Sil gave a composition with a creamy consistency low enough in viscosity to pour like a thick syrup and high enough to prevent the aluminum settling out. The combination of Quartec 503 and Cab-O-Sil proved particularly effective as a thickening agent for the composition of Example 1.

Examples 11 and 12

To further investigate cratering performance of explosives characteristic of the present invention as compared with known aluminum containing explosives, a series of test shots was conducted involving like amounts of the explosives of Example 1 (with 5 parts Cab-O-Sil) and Example 2, tested in like ground along with like amounts of Navy H-6 explosive and tritonal explosive. H-6, as known, is a 60/40 mixture of RDX and TNT, formulated with 5% wax and 20% aluminum particles, by weight. As also known, tritonal is an 80/20 mixture of TNT and aluminum particles. All shots were housed in steel jugs, and the charge in each instance weighed 1 pound and was buried a depth of 20 inches. Cratering performance for these shots was as follows:

TABLE 2

Example:	Depth	Diameter
1 (with 5 parts Cab-O-Sil).....	36.5	81
2.....	36	75
H-6.....	30.75	78.5
Tritonal.....	32.75	70.5

From the foregoing, and from the properties, characteristics and performance data available with respect to similar hydrazine and hydrazinium nitrate explosive compositions as presented in the aforesaid application 340,127 and U.S. Pat. 3,419,443, further variations in formulations, modes of formulation, and adaptations of explosive compositions of the present invention for various applications will be apparent to those skilled in the art, within the scope of the following claims.

What is claimed is:

1. An explosive composition comprising:
  - (a) an oxidizer reactant selected from the group consisting of
    - (1) hydrazinium nitrate,
    - (2) mixtures of hydrazinium nitrate and ammonium nitrate, and with a minor amount of an oxidizer salt selected from the group consisting of alkali metal nitrates, calcium nitrate, aluminum nitrate, hydrazinium perchlorate, alkali

metal perchlorates, calcium perchlorate, and mixtures thereof;

- (b) as a solvent for the oxidizer and as a gas producing reactant, a hydrazine containing liquid selected from the group consisting of hydrazine and mixtures thereof with ammonia; and
- (c) as a reducer reactant, finely divided aluminum; said oxidizer and said hydrazine containing liquid being present in detonatable proportions.

2. An explosive composition comprising the following constituents, present in the following relative percentages by weight:

Aluminum particles	From about 2% to about 45%.
NH ₃ and NH ₄ ⁺	0% to about 18%.
N ₂ H ₄ and N ₂ H ₅ ⁺	From about 6% to about 75%.
NO ₃ — or equivalent	From about 15% to about 70%.

wherein the nitrate anion or equivalent is present in one or more compounds selected from the group consisting of nitrate(s) and mixtures thereof with minor amounts of perchlorate(s).

3. An explosive composition according to claim 2, wherein the aluminum particles are present in substantially stoichiometric proportion with respect to the nitrate or equivalent.

4. The explosive composition of claim 2, at least principally comprising aluminum particles substantially uniformly dispersed in hydrazinium nitrate and ammonium nitrate dissolved in hydrazine and ammonia with the hydrazinium and ammonium ions in labile equilibrium.

5. The explosive composition of claim 2, further comprising a thickening and/or gelling agent present in an amount sufficient to provide the composition with the rheological properties of a solid and insufficient to render a composition nondetonatable.

6. An explosive composition according to claim 5, wherein said gelling agent is present in an amount less than about 10%, and is selected from the group consisting of expanded silica, Quartec, and mixtures thereof.

7. An explosive composition according to claim 2, further comprising a desensitizing agent, present in an amount insufficient to render the composition nondetonatable.

8. An explosive composition according to claim 7, wherein said desensitizing agent is present in an amount less than about 20% by weight and is selected from the group consisting of water, glycerin, glycol, hydrocarbon oil, wax and mixtures thereof.

9. An explosive composition according to claim 2, wherein the nitrate or equivalent ion is present essentially in the form of hydrazinium nitrate.

10. An explosive composition according to claim 2, wherein said nitrate ion or equivalent is present in a form consisting essentially of a mixture of hydrazinium nitrate and ammonium nitrate.

11. An explosive composition according to claim 2, wherein said nitrate ion or equivalent is present in the form of a mixture of stable hydronitrogen salts together with one or more metal salts in minor proportion by weight.

12. An explosive composition according to claim 11, wherein said one or more metal salts is selected from the group consisting of alkali metal nitrates, calcium nitrate, aluminum nitrate, alkali metal perchlorates, calcium perchlorate, and mixtures thereof.

13. The explosive composition of claim 5, at least principally comprising aluminum particles substantially uniformly dispersed in hydrazinium nitrate and ammonium nitrate dissolved in hydrazine and ammonia with the hydrazinium and ammonium ions in labile equilibrium, with the aluminum particles being present in substantially stoichiometric proportion with respect to the oxidizer.

14. An explosive composition according to claim 13, wherein said gelling agent is selected from the group consisting of expanded silica, Guartec, and mixtures thereof.

15. An explosive composition according to claim 14, further comprising a desensitizing agent, present in an amount insufficient to render the composition nondetonatable.

16. An explosive composition comprising the following constituents, present in the following relative percentages by weight:

Aluminum particles --- From about 20% to about 35%.
 NH_3 and NH_4^+ --- 0% to about 10%.

N_2H_4 and N_2H_5^+ --- From about 15% to about 30%.
 NO_3^- or equivalent --- From about 25% to about 55%.

wherein the nitrate anion or equivalent is present in one or more compounds selected from the group consisting of nitrate(s) and mixtures thereof with minor amounts of perchlorate(s).

17. An explosive composition according to claim 16, wherein the aluminum particles are present in substantially stoichiometric proportion with respect to the nitrate or equivalent.

18. The explosive composition of claim 16, at least principally comprising aluminum particles substantially uniformly dispersed in hydrazinium nitrate and ammonium nitrate dissolved in hydrazine and ammonia with the hydrazinium and ammonium ions in labile equilibrium.

19. The explosive composition of claim 16, further comprising a thickening and/or gelling agent present in an amount sufficient to provide the composition with the rheological properties of a solid and insufficient to render a composition nondetonatable.

20. An explosive composition according to claim 19, wherein said gelling agent is present in an amount less than about 5%, and is selected from the group consisting of expanded silica, Guartec, and mixtures thereof.

21. An explosive composition according to claim 16, further comprising a desensitizing agent, present in an amount insufficient to render the composition nondetonatable.

22. An explosive composition according to claim 21, wherein said desensitizing agent is present in an amount less than about 10% by weight and is selected from the group consisting of water, glycerin, glycol, hydrocarbon oil, wax and mixtures thereof.

23. An explosive composition according to claim 16, wherein the nitrate or equivalent ion is present essentially in the form of hydrazinium nitrate.

24. An explosive composition according to claim 16, wherein said nitrate ion or equivalent is present in a form consisting essentially of a mixture of hydrazinium nitrate and ammonium nitrate.

25. An explosive composition according to claim 16, wherein said nitrate ion or equivalent is present in the form of a mixture of stable hydronitrogen salts together with one or more metal salts in minor proportion by weight.

26. An explosive composition according to claim 25, wherein said one or more metal salts is selected from the group consisting of alkali metal nitrates, calcium nitrate, aluminum nitrate, alkali metal perchlorates, calcium perchlorates, and mixtures thereof.

27. The explosive composition of claim 19, at least principally comprising aluminum particles substantially uniformly dispersed in hydrazinium nitrate and ammonium nitrate dissolved in hydrazine and ammonia with the hydrazinium and ammonium ions in labile equilibrium, with the aluminum particles being present in substantially stoichiometric proportion with respect to the oxidizer.

28. An explosive composition according to claim 27, wherein said gelling agent is selected from the group consisting of expanded silica, Guartec, and mixtures thereof.

29. An explosive composition according to claim 28,

further comprising a desensitizing agent, present in an amount insufficient to render the composition nondetonatable.

30. An explosive composition comprising the following constituents, present in approximately the following relative percentages by weight:

	Percent
Aluminum particles	33
NH_3 and NH_4^+	10
N_2H_4 and N_2H_5^+	19
NO_3^- or equivalent	38

wherein the nitrate anion or equivalent is present in one or more compounds selected from the group consisting of nitrate(s) and mixtures thereof with minor amounts of perchlorate(s).

31. The explosive composition of claim 30, at least principally comprising aluminum particles substantially uniformly dispersed in hydrazinium nitrate and ammonium nitrate dissolved in hydrazine and ammonia with the hydrazinium and ammonium ions in labile equilibrium.

32. The explosive composition of claim 30, further comprising a thickening and/or gelling agent present in the amount of less than about 5% by weight.

33. An explosive composition according to claim 30, further comprising a desensitizing agent, present in an amount insufficient to render the composition nondetonatable.

34. An explosive composition according to claim 30, wherein said nitrate ion or equivalent is present in a form consisting essentially of a mixture of hydrazinium nitrate and ammonium nitrate.

35. The explosive composition of claim 32, at least principally comprising aluminum particles substantially uniformly dispersed in hydrazinium nitrate and ammonium nitrate dissolved in hydrazine and ammonia with the hydrazinium and ammonium ions in labile equilibrium.

36. An explosive composition according to claim 35, wherein said gelling agent is a mixture of expanded silica and Guartec.

37. An explosive composition according to claim 36, further comprising a hydrocarbon oil desensitizing agent, present in an amount insufficient to render the composition nondetonatable.

38. The method of compounding an explosive composition, comprising:

- preparing a first non-explosive liquid component selected from the group consisting of hydrazine and hydrazine having a non-explosive amount of one or more oxidizer salts dissolved therein;
- preparing a second, normally non-explosive solid component at least principally comprising one or more oxidizer salts in particulate form;
- mixing the above first component with the above second component with adequate agitation to cause at least a substantial portion of the second component to dissolve in the first component and provide an explosive mixture; and
- adding to the mixture finely divided aluminum powder while maintaining adequate agitation to provide a substantially homogeneous distribution of the aluminum powder in the explosive mixture.

39. The method of claim 38, wherein the proportions of the compounded ingredients are approximately as follows, expressed as relative percentages by weight:

Aluminum particles	2-45
Ammonium nitrate	2-45
Hydrazine	6-75

40. The method of claim 38, wherein the proportions of the compounded ingredients are approximately as follows, expressed as relative percentages by weight:

Aluminum particles	20-35
Ammonium nitrate	32-70
Hydrazine	15-30

41. The method of claim 38, wherein the proportions of the compounded ingredients are approximately as follows, expressed as relative percentages by weight:

Aluminum particles	33
Ammonium nitrate	48
Hydrazine	19

42. The method of claim 38, comprising mixing of the hydrazine, oxidizer salt(s) and aluminum particles under elevated temperature and/or vacuum conditions for a sufficient time to remove at least most of the free ammonia therefrom.

43. The method of claim 42, wherein the mixed composition contains the following ingredients in the following relative percentages by weight:

Aluminum particles	2-45
N ₂ H ₅ NO ₃	21-95
N ₂ H ₄	3-77

44. The method of claim 42, wherein the mixed composition contains the following ingredients in the following relative percentages by weight:

Aluminum particles	20-35
N ₂ H ₅ NO ₃	38-83
N ₂ H ₄	7-30

45. The method of claim 42, wherein the mixed composition contains the following ingredients in the following relative percentages by weight:

Aluminum particles	33
N ₂ H ₅ NO ₃	57
N ₂ H ₄	10

46. The method of compounding an explosive composition according to claim 38, further comprising adding to the mixture a thickening and/or gelling agent while maintaining agitation of the mixture at least until thickening and/or gelation thereof begins, the said thickening and/or gelling agent being present in an amount sufficient to provide the final composition with the rheological properties of a solid and insufficient to render the final composition nondetonatable.

47. The method of claim 46, wherein the proportions of the compounded ingredients are approximately as follows, expressed as relative percentages by weight:

Aluminum particles	2-45
Ammonium nitrate	2-45
Hydrazine	6-75

48. The method of claim 46, wherein the proportions of the compounded ingredients are approximately as follows, expressed as relative percentages by weight:

Aluminum particles	20-35
Ammonium nitrate	32-70
Hydrazine	15-30

49. The method of claim 46, wherein the proportions of the compounded ingredients are approximately as follows, expressed as relative percentages by weight:

Aluminum particles	33
Ammonium nitrate	48
Hydrazine	19

50. The method of claim 46, comprising mixing of the hydrazine, oxidizer salt(s) and aluminum particles under elevated temperature and/or vacuum conditions for a sufficient time to remove at least most of the free ammonia therefrom.

51. The method of claim 50, wherein the mixed composition contains the following ingredients in the following relative percentages by weight:

Aluminum particles	2-45
N ₂ H ₅ NO ₃	21-95
N ₂ H ₄	3-77

52. The method of claim 50, wherein the mixed com-

position contains the following ingredients in the following relative percentages by weight:

Aluminum particles	20-35
N ₂ H ₅ NO ₃	38-83
N ₂ H ₄	7-30

53. The method of claim 50, wherein the mixed composition contains the following ingredients in the following relative percentages by weight:

Aluminum particles	33
N ₂ H ₅ NO ₃	57
N ₂ H ₄	10

54. The method of claim 38, wherein the first non-explosive liquid component comprises hydrazine having dissolved therein less than about 20% ammonium nitrate by weight, and wherein said second component consists essentially of ammonium nitrate.

55. The method of claim 54, wherein the proportions of the compounded ingredients are approximately as follows, expressed as relative percentages by weight:

Aluminum particles	2-45
Ammonium nitrate	2-45
Hydrazine	6-75

56. The method of claim 54, wherein the proportions of the compounded ingredients are approximately as follows, expressed as relative percentages by weight:

Aluminum particles	20-35
Ammonium nitrate	32-70
Hydrazine	15-30

57. The method of claim 54, wherein the proportions of the compounded ingredients are approximately as follows, expressed as relative percentages by weight:

Aluminum particles	33
Ammonium nitrate	48
Hydrazine	19

58. The method of claim 54, comprising mixing of the hydrazine, ammonium nitrate and aluminum particles under elevated temperature and/or vacuum conditions for a sufficient time to remove at least most of the free ammonia therefrom.

59. The method of claim 58, wherein the mixed composition contains the following ingredients in the following relative percentages by weight:

Aluminum particles	2-45
N ₂ H ₅ NO ₃	21-95
N ₂ H ₄	3-77

60. The method of claim 58, wherein the mixed composition contains the following ingredients in the following relative percentages by weight:

Aluminum particles	20-35
N ₂ H ₅ NO ₃	38-83
N ₂ H ₄	7-30

61. The method of claim 58, wherein the mixed composition contains the following ingredients in the following relative percentages by weight:

Aluminum particles	33
N ₂ H ₅ NO ₃	57
N ₂ H ₄	10
